UNITED STATES PATENT OFFICE.

THOMAS J. ROBERTS, OF ATLANTA, GEORGIA.

MOTOR-STARTING DEVICE.

1,080,482.

Specification of Letters Patent.

Patented Dec. 2, 1913.

Application filed February 9, 1912. Serial No. 676,492.

To all whom it may concern:

Be it known that I, THOMAS J. ROBERTS, a citizen of the United States, residing at Atlanta, in the county of Fulton and State of Georgia, have invented certain new and useful Improvements in Motor-Starting Devices; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in motor starters and consists essentially in the provision of means whereby compressed air is utilized for imparting the initial rotary movement to the crank shaft and drawing in a charge and exploding, thus starting the engine.

My invention consists of a simple and efficient device of this nature having various details of construction and combinations and arrangements of parts which will be hereinafter fully described, shown in the accompanying drawings and then specifically defined in the appended claims.

My invention is illustrated in the accompanying drawings, in which:

Figure 1 is a central sectional view through a portion of an automobile showing the application of my invention thereto. Fig. 2 is an enlarged longitudinal sectional view through a portion of the crank shaft and cylinder with piston movably mounted therein. Fig. 3 is a cross sectional view on line 3—3 of Fig. 2, and Fig. 4 is a detail in elevation of a hollow spiral shaft.

Reference now being had to the details of the drawings by letter, A designates the end of a motor shaft having clutch recesses A' in one end thereof, and B designates a cranking shaft to which the clutch member B' is held by means of a pin B² and provided with teeth adapted to engage the recesses A' in the end of the motor shaft. A cylinder, designated by letter C, has apertured ends D and E through which the crank shaft B has a slight longitudinal movement.

Loosely mounted upon the crank shaft is a hollow cylindrical member F, having contracted ends F' and F² which terminate respectively in the shoulders H and H', and the circumference of said cylinder F is pro-

vided with spiral grooves I. A piston, designated by letter J, is mounted upon said cylinder and has a movement independent thereof and is provided with packing rings 60 J' in the circumference, and fastened to said piston are the keys K which engage said spiral grooves and serving, when the piston is moved independent of the cylinder, to impart a rotary movement to the latter. 65 Leading into said cylinder is a compressed air duct L, which duct is regulated by means of a valve N fixed upon one end of the stem N', which has a valve N² at its other end regulating the exhaust port O as well as 70 the inlet port O'. Said valve N is mounted intermediate the piston J and the head or end D and is adapted, as the piston moves to the left and comes in contact with the valve, to move the latter to its seat about 75 the marginal edge of the duct L, while, when the piston moves in the opposite direction and comes in contact with a lug P upon the stem N', it will cause the valve N² to close the exhaust port O and open the port or 80 duct O'.

A clutch collar R is fastened to the shaft B by means of a pin R' and is provided with teeth R^x upon one end, which are held in mesh with the teeth R² formed upon the adjacent contracted end of the cylinder F by means of a coiled spring R⁵ which is interposed between the washer R⁴ and a washer R⁶, the latter being positioned about the collar R. A fixed bearing member R³ receives loosely the shaft B and a coiled spring R⁵ is interposed between the washer R⁴ upon the shaft which abuts against the bearing member R³ and a flange upon the collar R, said spring serving to cause the teeth 90 R² and R^x to intermesh and to return the shaft B to its normal position after the engine has been cranked.

An air supply tank is shown and designated by letter S and in which air compressed by any suitable mechanism is contained, and a pipe S' leads from said tank to the cylinder S² in which a piston S³ is mounted, which latter is provided with two ducts S⁴ and S⁵, the latter of which, when in 100 registration with a port S⁶, affords communication between the pipe S' and the duct S⁵ and the pipe S⁷ which communicates with the cylinder S². A second pipe S¹¹ also leads from the air tank and communicates with the 105 port O'. The pipe S⁷ leads to and communicates with the port L and the duct S⁴, when

the piston S^3 is at its farthest outer throw, communicates with the exhaust port S^8 . A stem, designated by letter S^9 , is fixed to the piston S^3 , and a spring S^{10} is fixed to the flange of the cylinder and engages the head of said stem and serves to hold the piston normally at its farthest outer throw.

In operation, when it is desired to crank the engine by use of compressed air, the operator, by depressing the stem S^9 under the tension of the spring S^{10} , may cause the duct S^5 to come into registration with the opening through which the pipe S' communicates with the cylinder S^2 , thus allowing compressed air to pass through the pipe S' and the duct L where the pressure bearing against the valve N will cause the same to unseat. As the valve unseats, pressure bearing against the piston J will cause the same to move and with it the cylinder F a short distance. As the cylinder F moves forward, the clutch collar R will also be moved a short distance and with it the shaft B to which it is keyed, the movement being sufficient to cause the teeth upon the clutch collar B' to mesh with the teeth upon the engine shaft A . The forward movement of the cylinder F will be limited by the shoulders H' coming in contact with the adjacent end of the cylinder C . A further forward movement of the piston J by the air pressure acting upon the face thereof will, by reason of the keys K positioned in the spiral grooves in the cylinder, cause the latter to rotate and with it the clutch collar R and, by reason of the teeth R^2 and R^x being in mesh with one another, a rotary movement will be imparted to the shaft B by reason of the collar R being keyed thereto. A key J^2 , shown in Fig. 3 of the drawings, engages registering grooves formed in the cylinder and circumference of the piston and serves to prevent the latter from turning as it reciprocates. When the piston J in its forward movement comes in contact with the lug P upon the valve stem N' , longitudinal movement will be imparted to the latter, causing the valve N^2 to close the exhaust O and open connection between the port O' and the interior of the cylinder, thus allowing compressed air to be introduced into the right hand end of the cylinder to cause the piston to return to its starting position, the supply of air which is introduced through the pipe O^2 being direct from the cylinder S . When the operator releases pressure upon the stem S^9 , the spring S^{10} will return the piston S^3 to its outer limit, throwing the duct S^4 into communication with the exhaust S^8 and closing the supply port S^6 , thus allowing the air intermediate the left end of the cylinder and the piston to exhaust through the port L and pipe S^7 . When the piston J approaches its starting position, it will contact with the valve N and cause the same to seat simul-

taneously with the closing of the valve N^2 and opening of the exhaust port O leaving the apparatus in position for a repetition of the cranking operation.

When it is desired to crank the engine by hand, the operator by attaching a crank to the projecting end of the shaft B and engaging the pin d may cause the same to be given a slight longitudinal movement sufficient to disengage the intermeshing teeth R^x and R^2 and throw the clutch B' in mesh with the teeth upon the motor shaft A , thus cranking the engine in the usual manner independent of the piston and grooved cylinder.

80

What I claim to be new is:—

1. A starting device for motors comprising a spring-pressed cranking shaft, a cylinder in which the same is mounted, a clutch upon said shaft, a hollow cylindrical member loosely mounted upon said shaft within said cylinder and having spiral grooves in its circumference, a piston mounted upon said cylindrical member, keys projecting from the piston and engaging said grooves, means for preventing the piston from rotation, automatically-operated valves regulating ports communicating with the cylinder on opposite sides of the piston through which compressed air is adapted to pass to act upon the piston, and means for controlling the compressed air which acts upon the piston, as set forth.

85

2. A starting device for motors comprising a spring-pressed cranking shaft, a cylinder in which the same is mounted, a clutch upon said shaft, a hollow cylindrical member loosely mounted upon said shaft within said cylinder and having spiral grooves in its circumference, a piston mounted upon said cylindrical member, keys projecting from the piston and engaging said grooves, means for preventing the piston from rotation, valves regulating ports communicating with the cylinder on opposite sides of the piston through which ports compressed air is adapted to pass to act upon the piston, a stem connecting said valves, a projection upon the stem against which the piston is adapted to contact to cause a longitudinal movement to be imparted to the stem, and means for controlling the compressed air which acts upon the piston, as set forth.

90

3. A starting device for motors comprising a spring-pressed cranking shaft, a cylinder in which the same is mounted, a clutch upon said shaft, a hollow cylindrical member loosely mounted upon said shaft within said cylinder and having spiral grooves in its circumference, a piston mounted upon said cylindrical member, keys projecting from the piston and engaging said grooves, a longitudinally disposed key projecting from the inner surface of the cylinder engaging a groove in the circumference of the piston,

automatically - operated valves regulating ports communicating with the cylinder on opposite sides of the piston through which ports compressed air is adapted to pass to act upon the piston, and means for controlling the compressed air which acts upon the piston, as set forth.

4. A starting device for motors comprising a spring-pressed cranking shaft, a cylinder in which the same is mounted, a clutch upon said shaft, a hollow cylindrical member loosely mounted upon said shaft within said cylinder and having spiral grooves in its circumference, said member having a contracted portion movable through an opening in the head of the cylinder and terminating at its inner end in a shoulder, adapted to contact with the end of the cylinder to limit the longitudinal throw of said member in one direction, a piston mounted upon said member, keys fixed to the piston and projecting into said spiral grooves, means for holding the piston against rotation, automatically-operated valves regulating ports communicating with the cylinder on opposite sides of the piston through which ports compressed air is adapted to pass to act upon the piston, and means for controlling the compressed air which acts upon the piston, as set forth.

5. A starting device for motors comprising

ing in combination with a motor shaft a spring-pressed cranking shaft, a cylinder in which the same is mounted, a clutch upon said cranking shaft, a hollow cylindrical member loosely mounted upon said cranking shaft within said cylinder and having a contracted portion movable through an opening in one end of the cylinder, teeth upon the contracted end of said member, a toothed clutch pinned to the cranking shaft and adapted to engage the teeth upon said member, another clutch member carried by the cranking shaft and adapted to engage the motor shaft, the circumference of the cylindrical member having spiral grooves, a piston mounted upon said member having keys engaging said grooves, means for holding the piston against rotation, automatically-operated valves regulating ports communicating with the cylinder on opposite sides of the piston through which ports compressed air is adapted to pass to act upon the piston, and means for controlling the compressed air which acts upon the piston, as set forth.

In testimony whereof I hereunto affix my signature in the presence of two witnesses.
